CLAIM

The ornamental design for a square cover for receiving a flexible conduit from a garage door sensor.

DESCRIPTION

FIG. 1 is a top, side, front perspective view of a square cover for receiving flexible conduit from a garage door sensor; FIG. 2 is a top, side, rear perspective view thereof; FIG. 3 is a front view thereof;

FIG. 4 is a side view thereof, it being understood the other side is a mirror image thereof;

FIG. 5 is a top view thereof, it being understood that the bottom is a mirror image thereof; and,

FIG. 6 is a perspective view thereof shown in use. The conduit is shown with a symbolic break in its length. The appearance of any portion of the article between the break lines forms no part of the claimed design.

The broken lines shown represent unclaimed subject matter and form no part of the claimed design.
